UNITED STATES PATENT OFFICE.

SETH WHEELER, OF ALBANY, NEW YORK, ASSIGNOR TO MAXIMILIAN MORIZ AND HEINRICH KUMMER, OF BERLIN, GERMANY.

APPARATUS FOR CUTTING, FOLDING, AND INTERFOLDING SHEETS OR UNITS.

No. 874,903.

Specification of Letters Patent.

Patented Dec. 24, 1907.

Application filed December 31, 1904. Serial No. 239,274.

To all whom it may concern:

Be it known that I, SETH WHEELER, a resident of Albany, in the county of Albany and State of New York, have invented certain new and useful Improvements in Apparatus for Cutting, Folding, and Interfolding Sheets or Units; and I do hereby declare the following to be a full, clear, and exact description of the invention, such as will enable others skilled in the art to which it appertains to make and use the same.

My invention relates to an improved apparatus for cutting, folding and interfolding, and more particularly to an apparatus for cutting a strip or strips of paper into sheets or units of two or more sheets, folding each sheet or unit into several leaves or flaps, interfolding the end flaps of adjacent sheets, or units, and piling such interfolded sheets, or units, the result being a package consisting of a series of any desired number of interleaved units or sheets for use in cabinets, such as toilet cabinets, in which the withdrawal of one sheet or unit exposes the terminal flaps of the next succeeding sheet or unit.

The object of the invention is to provide an apparatus which will perform the above functions, quickly and accurately, and permit the pile of folded sheets, or sections thereof to be removed from time to time without interrupting the operation of the apparatus.

The invention consists in certain novel features of construction and combinations and arrangements of parts as will be more fully hereinafter described and pointed out in the claims.

In the accompanying drawings, Figure 1 is a view in longitudinal section illustrating my improvements, and Fig. 2 is a top plan view with holding tapes removed.

1 and 2 represent two parallel rolls having trunnions at their ends, supported in frames 3. Also supported in the frames 3 back of rolls 1 and 2 are rolls 4, and behind rolls 4, feeding rolls 5 are located, all connected by a chain of gearing 6 and turn simultaneously to feed the paper strips 7, as many of said strips or sheets may be located one above the other as may be desired according to the number of sheets composed in the interfolded units or books.

The strips of paper are fed from feeding rolls 5 on to rolls 4, which latter are longi-

tudinally grooved to receive serrated cutters 8, carried by bars 9 and springs 10 are located behind the bars 9 and exert outward pressure thereon. The ends of bars 9 project outward beyond the ends of rolls 4 and into cam flanged stationary disks 11 which latter serve to hold back the cutters, until they reach a position adjacent to rolls 1, where the flanges of disks 11 are notched or recessed as shown at 12, permitting the springs 10 to force the cutters forward through the paper strips and sever the strips into sheets of the desired length, the bars 9 being drawn back by the cam shape of the recess or notches 12, until the rolls 4 again reach this position.

It will be seen that the ribs 15 project sufficiently high above the peripheries of the respective rolls 1 and 2 that when the web of paper is drawn over the rib and down upon the periphery of the roll, there will be a portion of the paper, drawn tight, which is unsupported, and at this point, the knives 8 will be able by engaging the paper to sever the same.

Above rolls 1 and 2 tapes 14, running over rollers 14', are provided for holding the cut sheets upon the rolls 1 and 2, and effectually guiding these down between the rolls, the centermost roller 14' carries the tapes from both sides, and this roller will be idle and free to respond to the movement of the tape which takes the strongest hold upon it, and at times will remain stationary. Both rolls 1 and 2 are provided at proper intervals with V shaped ribs 15, the rib on one roll being effective to press the paper sheets carried by the other roll into the groove 13 in such other roll and give to the sheets the impression upon which they are folded and thus insure a straight even fold and flap of uniform width.

On one end of one trunnion of each roll 1 and 2 grooved eccentrics 16 are secured, and rollers or pins 17 at the upper ends of racks 18 are located in the grooves of said eccentrics, so that as the latter turn, the racks will be reciprocated up and down. These racks 18 mesh with gear segments 19 on shafts 20 and also with gears 21 on shafts 22. Shafts 20 carry at regular intervals, stripper arms 23, which project into grooves 24 in rolls 1 and 2 and compel the release of the sheets from holding pins 25 beside grooves 13, which pins prevent slipping of the paper.

while being cut and while being given its fold impressions.

On shafts 22 folder blades 26 are secured and when the shafts are turned the blades 26 5 press the folded edges of the paper down on the pile carried by a movable platform 27 from which sections of the pile can be removed from time to time.

The operation of the machine is as follows:—The webs of paper fed by rolls 5 upon both sides of the machine pass to the receiving rolls 4 and thence to the oppositely moving central rolls 1, 2 the latter being provided with tapes 14 to conduct the sheets downward between the two central rolls, as before explained. Each of the cutters 8 is normally within the periphery of the roll 4 which carries it. At the proper time for cutting, namely when the cutter is opposite the 20 portion of paper drawn taut over the ridge or rib 15, the cutter will be projected, sever a sheet from the continuous web and by the action of the tapes, the sheet will be carried over its adjacent central roll and between 25 the central rolls with the sheet coming from the other central roll. It will be noticed that the cutters alternate in their action, the effect of which is to cause the ends of two sheets and the center of the third sheet to 30 meet at the moment when the impression rib 15 of one central roll and the groove 13 of the other central roll engage to mark the line of fold in the paper carried by the roll having the groove. At the same time, the sheet 35 having the folding mark is engaged in proximity to said folding mark by the points 25 on the central roll carrying such sheet to insure its being carried forward with said roll until removed by the action of a stripper 40 blade 23, which will carry the interleaved sheets to the file, where they are retained by the folders 26. When the sheet next to be folded is being thus carried forward to be deposited on the pile, the end of the sheet from 45 the other roll will follow it in the manner shown in Fig. 1. The reason for this is, that when the two sheets are pressed together between the central rolls the air will be exhausted from between them by the pressure 50 of said central rolls. The sheet at its cut portion which is there free to leave its roll will, therefore adhere to and follow the sheet held to the other roll by the pins 25. When the folded sheet from roll 2 and the end of 55 the sheet coming from roll 1 will be marked for folding and engaged by the pin 25 on said roll 1. The fold of this sheet will therefore be carried by roll 1 toward the left hand end of the pile and the forward end of the next 60 sheet coming over roll 2 will be carried with it in the manner and for the reason before explained and the upper member of the folded sheet coming from roll 1, will, when removed by the stripper, be deposited upon 65 the upper fold or member of the previous

sheet, which upper fold or member is shown in Fig. 1, against the roll 2 ready to be removed by the stripper 23.

The assembling of the sheets is preferably done upon a yielding table or platform 27 70 which descends as required by the accumulating paper. While I have shown a machine producing a single pile of sheets, it is obvious that the incoming web may be divided longitudinally in its passage through 75 the machine and two or more piles of sheets produced, depending upon the width of the parent webs.

A great many slight changes might be 80 made in the general form and arrangement of the parts described without departing from my invention and hence I do not restrict myself to the precise details set forth but consider myself at liberty to make such slight changes and alterations as fairly fall 85 within the spirit and scope of my invention.

Having fully described my invention what I claim as new and desire to secure by Letters-Patent, is:—

1. In an apparatus of the character de- 90 scribed, the combination with two rolls, of rolls beside said first-mentioned rolls, and carrying cutters, means for feeding sheets between said rolls, flanged cam disks controlling the operation of the cutters, and means 95 compelling the interfolding of the sheets or cut units.

2. In an apparatus of the character de- 100 scribed the combination with two rolls, rolls located beside the first-mentioned rolls and having longitudinal grooves therein, bars in said grooves projecting at their ends beyond the rolls, cutters on said bars, springs behind the bars pressing them outward, flanged disks into which the ends of the bars project 105 and which hold the cutters in the rolls, and said flanged disks having notches or recesses which permit the cutter to be forced outward by its springs to sever the strip and means for folding said severed sheets.

3. In an apparatus of the character de- 110 scribed, the combination with two rolls and means for feeding sheets over the respective rolls, of V-shaped longitudinal ribs on both rolls to press the paper sheets into grooves in 115 the other roll and impress folds in the sheets, and means for timing the feed of sheets or units between the rolls to compel the overlapping and interfolding of the sheets or units passing over one roll with the sheets or units 120 passing over the other roll.

4. In an apparatus of the character de- 125 scribed, the combination with two rolls, means for cutting strips into sheets or units of several sheets, and feeding the same over both rolls and down between them, and timing the feed of the sheets or units to compel them to overlap, of means for forming impression lines of fold in said sheets or units, vertical racks reciprocated vertically, strip- 130

pers operated by the racks and entering grooves in the rolls to strip the sheets or units therefrom, and folders operated by said racks for pressing down the folds or the 5 sheets or units.

5. In an apparatus of the character described, the combination with two rolls having longitudinal grooves therein, of pins or points beside the grooves, cutters constructed to sever a strip or strips into a sheet or units of several sheets, and means for forming folding impressions in the sheets and for forcing the same onto the points, tapes for feeding said sheets or units down between the rolls, and 10 the cutting operation so timed as to compel the sheets or units to overlap, strippers constructed to force the sheets or units from the pins or points, a table or platform to receive the folded sheets, and folders constructed to 15 fold and press down the folded sheets thereon.

6. In a folding machine of the class de-

scribed, the combination with a pair of cylinders provided with knives for folding the paper supplied in alternate directions, of means for delivering to the folding knives 25 two sheets at a time, said sheets in their length and juxtaposition being matched with the folding knives in such a way that the knives come to bear alternately in opposite directions upon or between the ends of the 30 two sheets before getting at the center portion of the adjacent or back sheet and means for carrying the folded paper alternately with each of the two cylinders to right and left. 31

In testimony whereof, I have signed this specification in the presence of two subscribing witnesses.

SETH WHEELER.
